UNITED STATES PATENT OFFICE.

HARVEY HUBBELL, OF BRIDGEPORT, CONNECTICUT; LOUIE E. HUBBELL EXECUTRIX
OF SAID HARVEY HUBBELL, DECEASED.

SOCKET SHELL.

Application filed September 29, 1923. Serial No. 665,621.

This invention relates to electric lamp socket shells, and particularly to an improved means for connecting together the body of the shell and the cap.

5 It has for an object to provide an improved means for connecting the cap and the body of the shell which may be locked by merely forcing the cap and the body together longitudinally without any relative rotative movement, 60
10 and which may be unlocked and disconnected by pressing inwardly on one side of the body and then pulling the cap and body apart longitudinally without any rotative movement.

It is a further object of the invention to 15 provide a securing means for this class of devices which will have a great advantage in manufacture over the present devices of this character.

With the foregoing and other objects in 20 view, I have devised the construction illustrated in the accompanying drawing forming a part of this specification, and in which corresponding elements are designated by similar reference numerals throughout the 25 various views. In said drawing,

Fig. 1 is a side elevation of a lamp socket shell assembled.

Fig. 2 is a longitudinal section through the connected portions of the body and cap 30 substantially on the line 2—2 of Fig. 3 looking in the direction indicated by the arrows and on an enlarged scale.

Fig. 3 is a transverse section substantially on line 3—3 of Fig. 2.

35 Fig. 4 is a view similar to Fig. 2 but looking in the opposite direction as indicated by arrows 4—4 of Fig. 3.

Fig. 5 is a top plan view of the body of the shell.

40 Fig. 6 is a side elevation thereof.

Fig. 7 is an end view of the cap.

Fig. 8 is a longitudinal section thereof, substantially on line 8—8 of Fig. 7, and

45 Fig. 9 is an elevation of a portion of the cap showing a slightly different construction of the securing elements carried by the cap.

As is the usual construction the shell comprises a body member 10 and a cap 11 which enclose the works of the socket comprising 50 the switch and the contacts, which are not shown as they form no part of my present invention. The shell is also adapted to carry the usual shade holder 12.

55 The body and cap are made of sheet metal and are adapted for telescoping engagement,

the upper end of the body being inserted in the cap. The body is provided in one side with a slot 13 leading from the end thereof adapted for the passage of the usual key for operating the switch or the guide 14 for the 60 pull chain 15, if a pull switch is employed. The provision of this slot also allows the portions of the body on opposite sides thereof to yield inwardly.

The end of the shell which is adapted to be 65 inserted in the cap is provided throughout the greater portion of its periphery with a series of parallel grooves 16 in the outer wall thereof leading from the end of the body and longitudinally thereof, and they are formed 70 preferably by pressing inwardly the walls of the body. I have shown these grooves as being formed by crimping or corrugating the walls of the shell, but they may be formed by cutting slots in these walls and in other ways, 75 and therefore, I have used the term "grooves" throughout the specification and claims as designating these clearance spaces for passage of the securing elements of the cap whether they are formed by pressing later- 80

ally the walls of the shell, by corrugating, by cutting slots in the walls, or any other way found desirable. As it will be obvious these 85 grooves may be formed in different ways. These different forms have not been illus-

trated. No grooves are provided adjacent one side of the slot 13, the body being provided instead with a pair of rectangular openings 17 spaced from the end of the body, and they are spaced from each other and from the 90 next adjacent groove 16 substantially the distance between two adjacent grooves. Dia- metrically opposite to these openings 17 the grooves are also omitted and the body is pro- 95

vided with a similar pair of rectangular openings 18. The cap is provided with a series of triangular teeth 19 and 20 which are spaced from each other substantially the distance between the grooves 16 and openings 17 and 18, these teeth being located at a dis- 100

tance from the open end of the cap and pref- erably formed by cutting the walls of the cap with an L-shaped slit and then forcing in- wardly the portion of the walls enclosed by this slit. It will be apparent that this opera- 105 tion will provide a substantially triangular tooth integral with the walls of the cap and projecting inwardly therefrom. In cutting and forming these teeth they are so cut that two adjacent teeth will point in opposite di- 110

rections as will be apparent from an inspection of the drawing.

In connecting the cap and body 12 the end of the body carrying the grooves is inserted 5 in the cap with a pair of teeth in the openings 18 and other teeth 19 and 20 extending into the grooves 16. By then giving a combined relative rocking and longitudinal movement between the cap and body member, the portion 10 21 of the body adjacent the slot 13 will yield inwardly to allow a pair of teeth to pass to the openings 17 on the diametrically opposite side of the body. It will be apparent that when the pair of teeth come into 15 alignment with the openings 17 the portion 21 will spring outwardly to bring the teeth into these openings, thus securely locking the cap and the body member together. It will be understood that the edges of the teeth and 20 the sides of the openings provide shoulders which engage for this purpose. If it is desired to separate these members, all that is necessary is to press inwardly on the yieldable portion 21 so as to move the openings 18 from 25 the teeth and then separate the members by a combined rocking and longitudinal movement in the opposite direction from that made in bringing the elements together. It will be apparent that in both of these operations 30 no relative rotative movement between the members is required. In fact, the members are locked against a rotative movement both by coaction of the teeth and the openings 17 and 18, and by coaction of the teeth and the 35 walls of the grooves 16. It is pointed out above that two adjacent teeth point in opposite directions, and they are preferably so located about the periphery of the cap that the pair of teeth in the openings 17 will point 40 in opposite directions from the teeth in the openings 18 on the opposite side of the body member. For example, in Fig. 3 the teeth in the openings 17 are shown as pointing toward each other while the teeth in the opposite 45 openings 18 are pointing away from each other. If the cap and body member should be connected with the teeth shifted around a distance corresponding to that between two teeth, then the teeth in the openings 17 would 50 be pointed away from each other but the teeth in the openings 18 would be pointed toward each other. Thus the straight edges of the teeth are always so arranged as to engage opposite sides of the openings and thus securely 55 lock the members against relative rotation in either direction.

In Figs. 1 to 8 the slits forming the teeth are shown at substantially right angles to each other so that one edge of a tooth is substantially parallel with the end of the cap. However, I may if desired incline this edge, as shown at 22 in Fig. 9, to form in effect hooks back of the teeth 19' and 20' so that when the cap and body member are connected the edges of the openings 17 and 18 will seat back

of the free ends of the teeth and will be securely locked, requiring a slight relative longitudinal movement of the members before they can be unlocked by pressing the yieldable portion 21 inwardly. 70

It will be apparent from the foregoing description that the securing means is a very simple one which has numerous advantages in manufacturing over the securing means now generally in use. It will also be apparent 75 that the cap and body member are securely locked together, and that they may be connected and disconnected by simple movements without the necessity of rotating one with respect to the other. 80

Having thus set forth the nature of my invention, what I claim is:

1. In a socket shell having telescoping sections, one of said sections having a plurality of grooves leading from one end thereof and 35 openings spaced from said end at opposite sides of said section, and the other section being provided with a series of triangular teeth projecting laterally therefrom and integral therewith, said teeth adapted to enter said 90 grooves and openings to secure the sections together the inner or transverse edges of the teeth being inclined outwardly from the free ends or points of the teeth toward the inlet end of the section to form in effect hooks to 95 engage side walls of said openings.

2. In a socket shell having telescoping sections, the inner sections being provided with a slot leading from one end thereof allowing a portion of the section at one side of the slot 100 to yield inwardly under pressure, said section being provided with an opening in said yieldable portion spaced from the end of the section and a similar opening on the opposite side of the section, said section being also provided with a plurality of grooves in the outer walls thereof leading from its end and spaced from each other and the openings corresponding amounts, and the outer section being provided with a series of angular slits in the wall 105 thereof with the portion of the wall at the angle of the slits bent inwardly to provide triangular teeth, said teeth adapted to enter the grooves and openings to secure the sections together and having their inner or 110 transverse edges inclined from the point toward the inlet end of the section to in effect form hooks to engage an edge of the respective openings and require relative longitudinal movement of the sections before the yieldable portion of the inner section can be 115 pressed inwardly. 120

3. In a socket shell having telescoping sections, the inner section being provided with a slot leading from one end thereof allowing a 125 portion of the section at one side of the slot to yield inwardly under pressure, said section being provided with a pair of spaced openings in said yieldable portion and a pair of similar openings on the opposite side of the 130

- section, said section being also provided with a plurality of grooves in the outer walls thereof leading from its end and spaced from each other and the openings corresponding amounts, and the outer section being provided with a series of angular slits in the wall thereof with the portion of the wall at the angle of the slits bent inwardly to provide triangular teeth, the adjacent slits throughout the circumference of the section being reversed so that adjacent teeth extend in opposite directions from the wall of the section, and said teeth adapted to enter the grooves and openings to secure the sections together.
- 5 4. In a socket shell having telescoping sections, the inner section being provided with a slot leading from one end thereof allowing a portion of the section at one side of the slot to yield inwardly under pressure, said section being provided with a pair of spaced openings in said yieldable portion and a pair of
- 10 similar openings on the opposite side of the section, said section being also provided with a plurality of grooves in the outer walls thereof leading from its end and spaced from each other and the openings corresponding amounts, and the outer section being provided with a series of angular slits in the walls thereof with the portion of the wall at the angle of the slits bent inwardly to provide 25 triangular teeth, the adjacent slits being reversed throughout the circumference of the section so that adjacent teeth extend in opposite directions from the wall of the section, 30 said teeth being adapted to enter the grooves and openings to lock the sections together, and also so arranged that the pair of teeth in one pair of said openings face toward each other and the pair of teeth in the other pair 35 of openings face away from each other.
- 15 In testimony whereof I affix my signature.
- 20 HARVEY HUBBELL.
